UNITED STATES PATENT OFFICE

JOHN MURRAY, OF NEW YORK, N. Y.

IMPROVEMENT IN WHISTLES FOR STEAM-ENGINES.

Specification forming part of Letters Patent No. 58,875, dated October 16, 1866.

To all whom it may concern:

Be it known that I, JOHN MURRAY, of the city, county, and State of New York, have invented a new and useful Improvement in Whistles for Steam and other Engines; and do hereby declare that the following is a full, clear, and exact description of the construction and operation of the same, reference being had to the accompanying drawings, making part of this specification, in which—

Figure 1 is a top view of my invention, and represents by dotted lines the lever removed from the post for purposes hereinafter explained; Fig. 2, a side elevation, and Fig. 3 a longitudinal section of same.

This invention relates to a peculiar arrangement of mechanism in connection with the bell of a steam-whistle, by which a variety of sounds or scale of notes may be produced, adapted to the conveyance of preconcerted signals; and consists in applying to the bell of the whistle (of a steam-engine) a sleeve, which slides freely on the exterior (or interior as the case may be) of the bell, said sleeve being actuated by levers under the control of the engineer, in such manner that the engineer can convey his orders to the brakeman and other attendants of a railroad or steamship with accuracy and facility.

Having described the nature of my invention, I will now describe its construction and mode of operation.

In the drawings, A represents the steam-pipe, leading from the dome or boiler of a steam-engine, and to which the whistle is attached. B is the hexagonal neck, containing a female screw, b', for connecting the whistle to the steam-pipe. C is the cup, which forms, with the tongue or plate D, the circular aperture or steam-exit E. F is the spindle, which sustains the bell G of the whistle. H is a sleeve, which encompasses the bell G, and slides freely thereon, the said sleeve being sustained and actuated by a gimbal or set of levers, I K, the outer or main lever, K, being sustained by and hinged to an arm, L, projecting from the top of the spindle F, as shown in the drawings. This outer lever has a handle, l', and near to the handle, but on its in-

ner side, a small projection or stop, m, which enters corresponding recesses n n¹ n² n³ n⁴, &c., in a post, O. To the post O is attached a spring, P, the object of the spring being to press the lever K against the post O, and, aided by the stop m and recess n, to hold the lever K, and, of course, the sleeve H, in any desired position in relation to the cup C of the whistle.

The operation of my invention is as follows: Suppose the lever K to be at its highest point, the stop m in the upper recess n; and the sleeve H resting on the cup C. Now, by lowering the lever so that the stop m may enter the recess n¹, the sleeve will be raised from the cup, and a sound produced corresponding (as it were) to D in alt of the musical gamut; and by lowering the lever still more, so as to permit the stop m to enter the recess n², a change of sound similar to C of the said gamut will be produced, and so on, and vice versa, until the notes of the musical scale may be sounded, (or the bell G may slide on its spindle, and thus perform the office of the sleeve H, if preferred;) and by a little practical use of my invention the engineer will be enabled to vary the sounds, so as to convey his orders to the brakeman and other attendants, as well as preconcerted signals on approaching danger, calls for help, &c. Furthermore, if a more rapid change of sound may be desired, in this case the engineer merely removes the lever K from the post O, and instead of the lever uses the links R R, suspended from said lever, as shown in Fig. 2.

Having described my invention, what I claim, and desire to secure by Letters Patent, is—

The sliding-sleeve H, the gimbal or levers I K, the post O, and spring P, when in combination with the whistle of a steam or other engine, substantially as and for the purposes described.

In testimony whereof I have hereunto set my signature.

JOHN MURRAY.
